UNITED STATES PATENT OFFICE

2,007,746

ACOUSTIC DEVICE

Abraham S. Ringel, Brooklyn, N. Y., assignor to
Radio Corporation of America, a corporation of
Delaware

Original application July 20, 1925, Serial No.
44,735, now Patent No. 1,868,019, July 19, 1932.
Divided and this application March 21, 1928,
Serial No. 263,378

18 Claims. (Cl. 179—115.5)

This invention relates to acoustic devices for use in reproduction of voice, music or other signals. It has for its object also the truer and more exact reproduction, constancy of volume and in general more faithful likeness to the original than heretofore.

It is known that whenever a vibration was impressed upon any vibratile body that there are certain frequencies at which reproduction will be most efficient while at all others more or less inefficiency occurs resulting in exaggeration of certain tones as well as other undesirable effects. This invention attempts to obviate these difficulties by so arranging the oscillatory member or members that different elements thereof will respond at their most efficient period of vibration at different frequencies thereby causing the reproduction to be more uniform and of a more constant volume as well as giving greater sensitivity and efficiency.

This invention also relates to telephony, telegraphy, and other allied arts. More specifically the arrangements herein disclosed represent what is commonly known as loud speakers or electrical reproducers and the like although it is not intended to limit its use to this particular field. It might as well be used with phonographs and other resonant reverberating systems. It is also useful wherever large amplitudes of vibration are desired at or within the audio frequency range which should be of constant value.

Other objects and advantages will be apparent upon reading the following disclosure including specification, claims and annexed drawings. This application is a division of a parent application filed by John Minton and myself on July 20, 1925, Serial No. 44,735, now Patent No. 1,868,019, granted July 19, 1932.

One embodiment of the invention is shown in the accompanying drawing in which,

Fig. 1 is a vertical cross section of the vibrating system,

Fig. 1a is a sectional view of a modification of the apparatus shown in Fig. 1,

Fig. 2 is a section through the line 2—2 of Fig. 1, and

Fig. 3 is a series of graphs of the sound characteristics of the device.

Fig. 4 is a diagrammatic view showing how the diaphragm will vibrate at a certain high frequency, and

Fig. 5 is a diagrammatic illustration of approved circuits for the apparatus.

In the drawing number 3 denotes an extended mounting plate (a portion only being shown in

the drawing) having an opening in which one end of a diaphragm or cone 54 is supported by a ring or number of strips 11 of resilient material such as rubber, leather or other materials or fabrics. Plate 3 not only serves to support the cone but also serves to prevent the vibrations from the rear thereof from affecting those emanating from the front. The frustum or cone 54 serves as the sound radiating medium and may be formed of some semi-rigid fabric such as paper, parchment, cardboard or of a light metal such as aluminum or duralumin.

At the rear of the cone is mounted a magnetic system 49 which may be a permanent magnet or an electro-magnet energized by coils 26 and 59. This magnet is provided with pole pieces 58 and 59 which are separated by a substantially circular flux gap 61 and a central pole piece 60 separated from pole 59 by a substantially circular flux gap 62.

The flux produced passes through the air gaps between the respective pole pieces. Within the air gaps are located cylindrical sleeves 52 and 57. These sleeves may be of copper, aluminum or other low resistant, electrically conductive material, or may be in the form of multi-turn coils mounted on proper brackets or supports. As shown in Fig. 1, cylindrical sleeves are used, riveted by means of rivets 55 to different parts of the cone 54 or fastened by any other suitable means. In Fig. 1a multi-turn coils 51a and 53a are mounted on suitable cylindrical supports 52a and 57a.

It has been found best to make the sleeves 52 and 57 as light as possible in order that they may respond to high frequencies more readily without absorbing too much energy by their inertia. As shown, sections 56 are cut out to decrease the weight of sleeve 52. Instead of terminating as shown, the frustum 54 may be extended to a point at its small end to form a full cone, in which case sleeves 52 and 57 would be made longer.

In the operation of the modification shown in Fig. 1, a variable undulating or alternating electrical current is caused to flow in the coils 51 and 53 in accordance with the vibrations which are desired to be impressed upon the cone 54. These currents will induce variable circular eddy currents in sleeves 52 and 57, in a manner well known in the art. A variable force acting on conductors 52 and 57 will result due to the action of the permanent magnet fields in air gaps 61 and 62 on the currents in sleeves 52 and 57. The magnitude of these forces, as is well known, is

- directly dependent on the length of conductor, strength of current, and strength of the steady magnetic field. The direction of the force will be such as to move the cone along its axis. In 5 Fig. 1a where a pair of coils 51a and 53a attached to the cones are used to carry the modulated current instead of the sleeves 52 and 57, the coils 51 and 53 will of course be dispensed with. The action however will be the same.
- 10 As shown, the sleeve 52 is connected to an outer part of cone 54 and therefore will produce a greater response to vibrations of lower frequency, when the cone vibrates as a whole, while sleeve 57 being connected to one end of the cone, 15 will be more responsive to vibrations of a high frequency producing nodes and anti-nodes along the length of the cone 54. This action of the sleeves may be aided by permitting only the lower frequencies in the outer winding 51 while 20 the higher frequencies are confined to the inner winding 53 by any suitable circuit arrangements such, for example, as those shown in the application of John Minton and myself, Serial No. 35,893, filed June 9, 1925. Fig. 5 illustrates diagrammatically 25 a circuit corresponding to the circuit shown in Fig. 2 of application S. N. 35,893. The condenser 17 keeps the low frequencies out of the inner winding 53a and the inductance 18 keeps the high frequencies out of the outer winding 51a.
- 30 The outer portion of the cone, particularly where the cylinder 52 is fastened to it, will be hard to set in vibration at higher frequencies because of the large mass of cylinder 52 and for this reason will act as a nodal region for high 35 frequency vibrations. The form of vibration of the cone for higher frequencies will then be somewhat as shown in Fig. 4 the portions b and c will vibrate in sections, the portion a where the sleeve 52 joins the cone being a nodal region for 40 the high frequency vibrations. The actual motion of the cone will then be a back and forth motion similar to that of a piston combined with the sectional vibration or whipping action. For moderately high frequencies the piston action 45 will be almost entirely effective. However, as the first frequency at which this whipping action of the cone becomes more pronounced, the amplitude of this mode of vibration becomes much greater than that of the pure piston motion and 50 as a result much more sound is radiated at this frequency. This mode of vibration occurs not only at this one frequency but at still higher frequencies. It can thus be seen that the two 55 actuating sleeves will, in connection with the cone be responsive to different resonant frequencies thereby causing a more constant response than would be obtainable with a single operator. While I have shown the cone 54 as operated by the eddy currents in the sleeves 52 and 57 (Fig. 1) and by the current flow in coils 51a and 53a (Fig. 1a) it will be understood that any other desired means may be used to operate the sleeves.
- 60 If the vibrating system shown is analyzed and the sound characteristics thereof plotted, curves similar to those shown in Fig. 3 will result, ordinates representing audibility and abscissas representing frequency. Curve 1 shows the characteristic of the rear portion of the cone to which sleeve 57 is attached while curve 2 shows that of the front or large portions of the cone. If these two portions are operated jointly from the same source or by the same current, the two 65 characteristic curves will be superimposed upon

each other giving a resultant 3 which shows a smaller percentage of variation.

While I have shown the diaphragm for emitting the sound to be of conical shape it is understood that diaphragms of other shape which function in a similar manner may be used instead, without departing from the spirit of my invention. That for which I ask protection by Letters Patent is:—

1. In an acoustic device, a vibratile member, 10 an actuating element, means attaching said element to the outer portion of said member, and means responsive to high frequencies for vibrating the inner portion of said vibratile member whereby a nodal region is produced adjacent said 15 first named means.
2. In an acoustic device, a vibratile element, an actuating member carried by one portion of said element, said actuating member being of relatively large mass and means for vibrating 20 another portion of said element at high frequencies whereby a nodal region is produced in the region where said actuating member is attached to said vibratile element.
3. Acoustic apparatus comprising a vibratile 25 diaphragm system having an outer diaphragm portion more responsive at lower audible frequencies than at some higher audible frequencies, and a central portion more responsive at said 30 higher audible frequencies than at said lower audible frequencies, and separate means for vibrating each of said diaphragm portions.
4. Acoustic apparatus comprising a vibratile member, a coil responsive to high frequencies attached to said vibratile member for causing vibration thereof, and a coil responsive to low frequencies also attached to said vibratile member for causing vibration thereof. 35
5. Acoustic apparatus comprising a vibratile 40 diaphragm and a pair of separate windings for vibrating said diaphragm, one of said windings being responsive to high frequencies and the other of said windings being responsive to low frequencies.
6. Acoustic apparatus comprising a vibratile 45 diaphragm and a pair of separate windings for vibrating said diaphragm, one of said windings being adapted to respond to high frequencies and the other winding being adapted to respond to low frequencies, and a coil form secured to said 50 diaphragm at its smaller base, at least one of said windings being located on said coil form.
7. Acoustic apparatus comprising a frustum shaped diaphragm, a winding responsive to high 55 frequencies connected to said diaphragm immediately adjacent the smaller base thereof, and a second winding for said diaphragm located at a position more remote from said smaller base than the position of the first mentioned winding.
8. Acoustic apparatus comprising a magnet 60 system, means for producing sound waves, a pair of voice coils connected to said means for producing sound waves and arranged to be threaded by lines of force from said magnet system, one of said coils being adapted to respond to high frequencies and the other coil being adapted to respond to low frequencies, and circuits for supplying to each coil the frequencies to which it is adapted to respond. 65
9. Acoustic apparatus comprising a truncated 70 conical diaphragm, a voice coil responsive to high frequencies, a voice coil responsive to low frequencies, means for transferring mechanical vibrations from said coils to said diaphragm, said voice coil responsive to high frequencies being 75

connected to said diaphragm immediately adjacent its smaller base, a magnet system providing lines of force to thread said voice coils, separate circuits for energizing said voice coils separately 5 from a single source of energy, and a condenser connected in series in the circuit supplying energy to the voice coil responsive to high frequencies for substantially keeping low frequencies out of that voice coil.

10. Acoustic apparatus comprising a truncated diaphragm, a pair of separate voice coil windings connected with said diaphragm, means connecting at least one of said windings to said diaphragm immediately adjacent the smaller base thereof, circuits for separately supplying energy to said windings, and means in one of said circuits for causing a predomination of certain frequencies in the winding energized by that circuit.

11. Acoustic apparatus comprising a diaphragm, a plurality of voice coils connected with said diaphragm, means forming magnetic lines of force threading said voice coils, and circuits for supplying energy to said voice coils separately and at different frequencies.

12. A sound reproducer of the electrodynamic type comprising an electromagnetic system, a sound reproducing diaphragm and a plurality of windings movable with said diaphragm, means whereby said windings are responsive to different ranges of audio frequency notes, said windings operating in the field of said electromagnetic system for conjointly imparting vibrations to said diaphragm.

13. In a loud speaker, a diaphragm, a plurality of actuating coils connected to said diaphragm and movable therewith, a source of electric waves of frequencies extending over a substantial part of the audible spectrum, circuit connections between said source and said coils and means included in said circuit connections whereby one of said coils is rendered most responsive to a band of frequencies embracing a fractional part of the audible spectrum, and another of said coils is

rendered most responsive to a different fractional part of the audible spectrum.

14. A sound reproducer of the moving coil type comprising an electromagnetic system, vibratory sound reproducing means, a plurality of windings movable with said vibratory means and operable in the field of said electromagnetic system to actuate said means, and means whereby said windings are responsive to different ranges of audio frequency notes.

15. A loudspeaker having a diaphragm, a plurality of movable coils for actuating said diaphragm, a field magnet structure operatively associated with said coils, means for simultaneously connecting said coils in a circuit of variable impulses, and means whereby said coils accentuate different bands of frequencies.

16. In an electrodynamic translating device a plurality of windings movable to cut the lines of force in a magnetic system, means whereby said windings respond most efficiently to different bands of frequencies, and a single diaphragm surface actuated by said windings.

17. A sound reproducer of the electrodynamic type comprising an electromagnetic system, a single vibratory sound reproducing means, a plurality of windings movable with said single vibratory means and operable to cut the lines of force of said electromagnetic system to actuate said means, and means whereby said windings are responsive to different ranges of audio frequency notes.

18. In a loudspeaker, the combination of a magnet system adapted to provide magnetic lines of force, a plurality of independent coils mounted in operative relation to the pole pieces of said magnet system, said coils being positioned to cut said magnetic lines of force, means whereby each of said coils is efficiently responsive to a selected band of audio frequencies, and sound reproducing means controlled by said coils to reproduce practically the entire audible range of notes.

ABRAHAM S. RINGEL.
